CLAIM

The ornamental design for a fly bait container, as shown as described.

DESCRIPTION

FIG. 1 is a top and front perspective of a fly bait station showing my new design;

FIG. 2 is a front elevational view, broken away for the convenience of illustration, the rear being a mirror image thereof;

FIG. 3 is a side elevational view thereof;

FIG. 4 is a top plan view thereof;

FIG. 5 is a bottom plan view thereof; and,

FIG. 6 is an enlarged view of a portion of FIG. 1 showing increased detail thereof.

FIG. 4

FIG. 5

FIG. 3

FIG. 2
